DESIGN FOR A RING-BOAT TOY

David Davidson, Los Angeles, Calif.

Application February 15, 1945, Serial No. 117,965

Term of patent 3½ years

(Cl. D34—15)

To all whom it may concern:

Be it known that I, David Davidson, residing at Los Angeles, in the county of Los Angeles and State of California, have invented a new, original, and ornamental Design for a Ring-Boat Toy, of which the following is a specification, reference being had to the accompanying drawing, forming a part thereof.

The figures in the drawing are:

Fig. 1 is a side perspective view of a ring-boat toy showing my new design;

Fig. 2 is a cross-sectional view thereof taken on line 2—2 in Fig. 1.

I claim:

The ornamental design for a ring-boat toy, as shown.

DAVID DAVIDSON.
